HORTICULTURAL SPRAY OIL

Frank F. Lindstaedt, Oakland, Calif.

No Drawing. Application June 27, 1936,
Serial No. 87,736

9 Claims. (Cl. 167—28)

The invention relates to hydrocarbon oil and water emulsions such as used for horticultural spray purposes and more particularly to the inclusion in the hydrocarbon oil of certain toxicants.

As will be understood, hydrocarbon or petroleum oils have been extensively used in water emulsions for horticultural spray purposes for the control of insecticides and other parasites. In the case of some of the more resistant parasites the hydrocarbon oil must be used in relatively heavy deposits to insure a complete killing, or at least, an effective control of the parasite and such deposits are, in many instances, unsafe for the plant tissues. For this reason, it is common to include in hydrocarbon oil certain toxic materials which have been found to be specific for the control of certain insecticides and parasites and the use of which enables substantial reductions in the required hydrocarbon oil deposit. For many years nitrophenols have been known to possess insecticidal properties. Various of these nitrophenols have been used by themselves as insecticides, the most outstanding members of the family which have been used, being potassium 3-5 dinitro-ortho-cresylate, the ammonium and potassium salts of 3-5 dinitro-ortho-cresol and 3-5 dinitro-ortho-paracresol, ortho and para dinitrophenol, dinitroparachlorophenol and dinitro-ortho-cyclohexylphenol.

While these toxicants by themselves have been used with varying success as insecticides, ovicides and scalicides, they have heretofore never approached their optimum lethal properties when combined with a hydrocarbon oil in a water and oil spray emulsion. I have found that on the addition of these nitrophenols to various types of oil and water spray emulsions, a considerable portion of the toxicant withdraws from the oil phase of the emulsions and passes over to the water phase. Accordingly, while a considerable proportion of the toxicant may be added to the spray material only a very small fraction remains in the oil phase, while the remainder is carried off the plant structure by the water following the breaking of the emulsion. In accordance with the present invention, and as one of the principal objects thereof, I introduce means into the spray composition to prevent the transfer of the toxicant from the oil to the water phase as aforesaid, whereby substantially the entire proportion of the toxicant will remain with the oil on the plant structure and the full benefit of the toxicant thereby received.

As a further object of the present invention, I

provide, in the petroleum oil and water horticultural spray emulsion of the character described, an intermediate solvent which is effective to increase the solubility of the nitrophenols in the oil phase of the emulsions, whereby certain of these nitrophenols, which are ordinarily only sparingly soluble in the petroleum oil, may be added in sufficiently large quantities to realize a maximum toxicity of the oil and nitrophenol combination.

The invention possesses other objects and features of advantage, some of which, with the foregoing will be set forth in the following description of the preferred form of the invention. It is to be understood, however, that variations in the mode of effecting the invention, as explained in the description, may be adapted within the scope of the invention as set forth in the claims.

More specifically I have found that the nitrophenols may be held in the oil phase of the hydrocarbon oil and water spray emulsion by the use of an acidic emulsifying agent, and that in addition, by the use of certain vegetable and animal oils a greater amount of the nitrophenols can be dissolved in or exclusively carried by the hydrocarbon phase of the emulsion. Of the various derivatives or substituted products obtained from the nitrophenol parent, I have found that the most effective are dinitro-ortho-cyclohexylphenol, dinitro-ortho-cresol, and dinitro-para-chlorophenol. Dinitro-ortho-cyclohexylphenol may be at present obtained with either a 2-4 or a 3-5 arrangement of the NO_2 radical, and while either appears to be a highly effective toxicant for certain types of parasite control, preferably the 2-4 arrangement or, more specifically, the 2-4 dinitro-6-cyclohexylphenol has certain advantages, due to its greater solubility in hydrocarbon or petroleum oil and in having a slightly better toxicity.

The result of present tests indicate a general superiority of dinitro-ortho-cyclohexylphenol, but as above stated, the dinitrocresol and the dinitroparachlorophenol are also effective in many instances. The former, dinitrocresol, may be used in either the ortho or the para positions of the nitro atoms and the ammonium and potassium salts of these compounds are also effective, as above indicated.

A relatively small amount of the above toxicant in the hydrocarbon oil is all that is required in most instances to produce a substantially complete killing of the parasite and also enables substantial reductions in the amount of hydrocarbon oil required in the spray mix-

ture. I have found that from one-half to one and one-half per cent toxicant in the oil, is, for the most part, sufficient although if desired, and for certain types of work, may be increased over 5 this value. As above indicated, the addition of a toxicant to the oil enables a substantial reduction in the amount of oil which is required in the spray mixture, and which, in accordance with the present invention, may vary from one- 10 quarter to approximately three per cent of the water content for ordinary spray work. In the case of dormant spray this proportion of oil may ordinarily be considerably increased without injury to the plants.

15 Together with the toxicant and the hydrocarbon oil is embodied an acid reacting oil soluble emulsifier agent in the proportion ranging from approximately one-half to one per cent of the hydrocarbon oil. Particularly good results have 20 been obtained by the use of an emulsifier consisting of approximately fifty per cent naphthenic acid and fifty per cent sulphonated naphthenic acid. This emulsifier has been more specifically set forth and claimed in my co-pending 25 application, Serial Number 752,990, filed November 14, 1934. While I prefer this particular acid reacting emulsifier, others may be used, such as glycol oleate, glycerol oleate, oleic acid, etc.

I have further found that the solubility of 30 the nitrophenols in hydrocarbon oil may be substantially increased by the use of an intermediate solvent for the nitrophenols and the hydrocarbon oil. This is particularly important in the case of the more insoluble nitrophenols 35 and where the hydrocarbon oil is of a highly refined type having a high unsulphonatable residue. More specifically I have found that certain fatty oils will act as an intermediate solvent to considerably increase the solubility of the nitrophenols in the hydrocarbon oil. Among the vegetable group of the fatty oils are soya bean kettled oil, varnish makers hempseed oil, raw tung oil, and certain blended bodied vegetable oils, such as used for paint purposes. Of the animal 40 group, fish oils are preferable and of these I prefer a boiled vacuum kettled sardine oil, although fairly satisfactory results have been obtained by the use of other fish oils, such as herring oil. The proportion of these intermediate oil solvents depends to some extent, upon 45 the natural solubility of the toxicant and the desired concentration of the toxicant in the oil. For example, in the case of 3-5 dinitro-ortho-cyclohexylphenol, which is very sparingly soluble in hydrocarbon oil the amount of this compound 50 which may be dissolved in or carried by the hydrocarbon oil may be changed from approximately 0.3% without the use of the intermediate oil solvent to approximately 1.0% by the addition of approximately 3 to 5% of the intermediate solvent to the hydrocarbon oil. For the other nitrophenol toxicants above mentioned, the proportion of the intermediate oil solvent in the hydrocarbon oil may vary from 55 2% to 7% depending on the specific solvency of the intermediate solvent, the relative solubility of the toxicant and the amount of toxicant desired in the oil.

The presence of the intermediate oil solvent in the hydrocarbon oil, especially where the former is composed of a boiled, blown or polymerized oil, has a further beneficial effect in partially setting into a cellular structure in being sprayed and in holding the hydrocarbon oil against undue penetration into the plant tissues. This latter operation of certain of these oils has been more fully described in my copending application, Serial Number 24,359, filed May 10 31, 1935.

I claim:

1. An oleaginous product adapted for mixing with water for producing a horticultural spray comprising, a hydrocarbon oil, a dinitro-ortho-cyclohexylphenol, and an acidic emulsifying agent consisting of a combination of a naphthenic acid and a sulphonated naphthenic acid. 15

2. An oleaginous product adapted for mixing with water for producing a horticultural spray 20 emulsion comprising, a hydrocarbon oil, a nitrophenol, a fatty oil intermediate solvent for said nitrophenol and said hydrocarbon oil.

3. An oleaginous product adapted for mixing with water for producing a horticultural spray 25 emulsion comprising, a hydrocarbon oil, a nitrophenol, a vegetable oil intermediate solvent for said nitrophenol and said hydrocarbon oil, and an emulsifying agent.

4. An oleaginous product adapted for mixing 30 with water for producing a horticultural spray emulsion comprising, a hydrocarbon oil, a nitrophenol, a fish oil intermediate solvent for said nitrophenol and said hydrocarbon oil, and an emulsifying agent. 35

5. An oleaginous product adapted for mixing with water for producing a horticultural spray comprising, a hydrocarbon oil, 2-4 dinitro 6 cyclohexylphenol, naphthenic acid, sulphonated naphthenic acid, and a fish oil intermediate 40 solvent for said 2-4 dinitro 6 cyclohexylphenol and said hydrocarbon oil.

6. An oleaginous product adapted for mixing with water for producing a horticultural spray comprising, a hydrocarbon oil, a dinitro-ortho-cyclohexylphenol, an acidic emulsifier, and an unsaturated fatty oil intermediate solvent for said dinitro-ortho-cyclohexylphenol and said hydrocarbon oil. 45

7. An oleaginous product adapted for mixing 50 with water for producing a horticultural spray comprising, a hydrocarbon oil, a nitrophenol, an acidic emulsifier, and an unsaturated fatty oil intermediate solvent for said nitrophenol and said hydrocarbon oil.

8. An oleaginous product adapted for mixing with water for producing a horticultural spray comprising, a hydrocarbon oil, a dinitroresol, an acidic emulsifier, and an unsaturated fatty oil intermediate solvent for said dinitroresol and 60 said hydrocarbon oil.

9. An oleaginous product adapted for mixing with water for producing a horticultural spray comprising, a hydrocarbon oil, a nitrophenol, an acidic emulsifier, and an unsaturated vegetable 65 oil intermediate solvent for said nitrophenol and said hydrocarbon oil.

FRANK F. LINDSTAEDT.
